UNITED STATES PATENT OFFICE.

CHARLES E. COATS, OF NEW YORK, N. Y., ASSIGNOR TO COATS MACHINE TOOL COMPANY, INC., OF NEW YORK, N. Y., A CORPORATION OF NEW YORK.

GAGE.

1,347,207.

Specification of Letters Patent. Patented July 20, 1920.

Application filed October 6, 1919. Serial No. 323,726.

To all whom it may concern:

Be it known that I, CHARLES E. COATS, a citizen of no country, and a resident of the borough of Manhattan, city, county, and State of New York, have invented certain new and useful Improvements in Gages, of which the following is a specification.

This invention relates to improvements in gages, and more particularly to testing 10 gages of the liquid-column type.

The invention has for its objects to provide a gage of the class set forth constructed of a minimum number of parts which may be readily assembled and dismantled; 15 to simplify the construction and increase the durability and efficiency of the indicating-fluid reservoir; to provide more efficient means for adjusting the indicating means bodily relatively to the base of the gage; to provide improved means for varying the 20 capacity of the indicating-fluid reservoir; and to provide a gage of the type set forth so constructed as to increase the utility and durability thereof.

25 In the drawings, Figure 1 is a side elevation of the improved gage;

Fig. 2 a front elevation thereof;

Fig. 3 a vertical section on the line III—III of Fig. 2;

30 Fig. 4 a sectional plan on the line IV—IV of Fig. 2; and

Figs. 5 and 6 detail views, partly in vertical section illustrating the operation of the gage and the construction of the fluid reservoir.

Referring to the various parts by numerals, the base of the gage has an article-supporting block or plate 1 detachably held to the upper side thereof by suitable screws.

40 An angular member 2 is held to the block 1 by means of a clamping screw 3 which extends through an elongated slot in the horizontal portion of said member, whereby the member may be adjusted to shift the 45 upstanding article-supporting and alining portion thereof relatively to a vertically reciprocable plunger 4. The member 2 is formed with suitable guiding ribs 35 which slidably engage in grooves or channels in

50 the block 1, and the block 1 is preferably provided with a plurality of threaded sockets in either of which the screw 3 may be threaded, as more clearly shown in Figs. 2, 3 and 4.

55 The indicating means is supported above

the block 1 on the forward end of a vertically adjustable arm 5. The arm 5 is formed with an integral sleeve or collar 6 which embraces a vertical post 7 rigidly held at its lower end to the base of the gage. 60 The sleeve 6 and arm 5 are held against rotary movement about the post 7 by a key 8 held to the sleeve 6 by a suitable screw 36 and engaging in a key way 37 formed in the post, as more clearly shown in Figs. 3 65 and 4.

The lower end of sleeve 6 is threaded internally to receive the reduced threaded upper portion of an adjusting nut 9, which has a reduced threaded lower portion 70 screwed into the internally threaded upper end of a collar 10 and is also provided with a central aperture through which the post 7 extends. The threaded connections between the sleeve and nut and the collar 75 and nut are of opposite pitch and the threads are of low pitch, for example 40 pitch, to permit of fine adjustments of the arm 5 and sleeve 6 up or down relatively to the collar 10 by rotating the nut 9. The 80 arm 5, sleeve 6, nut 9 and collar 10 may be simultaneously and quickly moved up or down on the post 7 for coarse adjustments, by means of a pinion 11 which meshes with teeth 12 formed on the flattened forward 85 side of post 7 and is rotatable by a shaft 13 journaled in the collar 6 and having a finger wheel 14 fixed on one end thereof. The collar 10 has a split lower portion controlled by a clamping screw 32 for clamping 90 the collar on the post in its adjusted position.

The arm 5 is formed with a circular recess in the under side thereof adjacent its forward end, and is also formed with an 95 annular upstanding flange 15 on its upper side concentric with an aperture communicating with said recess. An indicating-fluid container, chamber or receptacle 16 of circular form and preferably constructed 100 of brass, is removably held in the recess in arm 5 by a closure member or cap 17 screwed into said recess and formed with a depending tubular extension through which the plunger or pin 4 slidably extends. The 105 vertical wall of reservoir 16 is relatively thick and is rigid, while the top and bottom walls thereof are thin and flexible. The bottom wall is preferably formed by turning the edge of a brass or other suit- 110

able metallic diaphragm 18 upwardly around the outer side of the undercut lower end of the circular vertical wall of the reservoir and soldering or otherwise securing the upturned edge of the diaphragm to said vertical wall so as to form a liquid-tight connection, the top, bottom and side walls of the reservoir becoming practically integral with each other.

- 10 The plunger 4 is provided with a slot or groove 33 into which a screw 34 threaded through cap 17 extends. Screw 34 prevents the plunger from dropping out of contact with a small metal disk 19 soldered or otherwise secured to the under side of the flexible diaphragm 18. The disk 19 serves to stiffen the central portion of the diaphragm and thereby augments or magnifies the action of the diaphragm in displacing the indicating fluid in the reservoir when the diaphragm is pressed upwardly by the plunger 4.

The upper flexible wall of the reservoir 16 is formed with a rigid tubular extension 20 which projects upwardly through arm 5 and the annular flange 15 formed on said arm and serves to support a glass indicating tube 21. The extension 20 is closed at its lower end except for a small central aperture which registers with the fluid passage in the glass tube 21. The glass tube is rigidly but detachably held at its lower end in the extension 20 by a nut 22 threaded into the upper end of the extension and bearing upon a metallic washer 38 which rests upon a suitable compressible packing ring 39. By unscrewing the cap 17, said cap and the plunger 4 may be disconnected from the arm 5, and the fluid reservoir and indicating tube 21 may then be withdrawn as a unit.

The capacity of the reservoir 16 may be varied to raise or lower the normal level of the indicating liquid in tube 21, by means of a screw 23 threaded through the arm 5 and engaging the flexible top wall of the reservoir. The tube 21 is protected by a tubular metallic casing 24 the front side of which is cut away intermediate the ends thereof to permit observation of the liquid level in the indicating tube. Two vertical posts 25 and 26 arranged at opposite sides of casing 24 are rigidly held to a support or bracket 27 tightly but removably clamped upon the casing 24 by means of a plate 28 and suitable screws threaded through said plate into said bracket. Three pointers 29 are slidably mounted on the post 25 for independent vertical adjustment, said pointers being frictionally held in their adjusted positions and being preferably formed with finger pieces, as shown, to facilitate adjustment thereof on the post. The usual graduated indicator plate, bar or leaf 30 is supported on the post 26 and is adjustable ver-

tically thereon, a suitable set screw 40 being provided for holding the plate or leaf 30 in its adjusted position. The tubular casing 24 is split at its lower end and is removably but rigidly held to the flange 15 70 on arm 5 by a split clamping ring 31, as clearly shown in Figs. 3 and 4. The liquid reservoir is filled in the usual way, by pouring the indicating liquid into the usual flaring funnel-shaped upper end of the indicator tube 21, the casing 24 being provided with the usual removable cap 41 at its upper end.

In using the gage, the lowermost pointer 29 is adjusted to register with the top of 80 the liquid column in tube 21 and the other two pointers are adjusted until they are spaced apart a distance on the scale plate 30 corresponding with the permissible variation in size of the articles to be tested from 85 a master piece or article of the desired size. The master piece is then placed on the block 1 and the clamping ring 10 lowered and arm 5 adjusted by means of the pinion 11 and finger wheel 14 until the plunger 4 almost engages the master piece. Collar 10 is then clamped to the post by tightening screw 32, and nut 9 is rotated slightly until plunger 4 engages the master piece and is forced upwardly, nut 9 being turned until the level of the liquid in tube 21 reaches the proper point between the two uppermost pointers. The gage is thus set and ready for use in testing the articles to determine whether or not they conform sufficiently closely with the master piece. If the level of liquid in tube 21 should rise above or fall below the lower pointer by reason of leakage, evaporation, or expansion and contraction due to changes in temperature, the liquid level may be adjusted to again register with the lower pointer by adjusting the screw 23 to increase or decrease the capacity of the reservoir 16 as may be required, thus avoiding the necessity 110 of entirely re-setting the gage.

What I claim is:

1. A device of the class set forth comprising a base, an upright post rigidly held to the base, a collar slidable on said post, means for holding the collar in its adjusted position, a laterally extending arm having an aperture through which the post extends, an adjusting nut slidable on the post and having right and left hand screw thread 115 connections with the arm and collar, an indicating-fluid container supported by said arm having a flexible lower wall, a transparent indicating tube communicating at its lower end with said container, and a plunger reciprocably supported on said arm below said container and adapted to flex the lower wall of the container when moved upwardly relatively to the arm.

2. A device of the class set forth compris- 130

ing a base provided with an article-supporting surface, an upright post held to the base and provided with a vertical series of teeth at one side thereof, a laterally extending arm having an aperture through which the post extends, a horizontally extending shaft journaled in said arm, a pinion on said shaft meshing with the teeth on the post, a finger wheel on one end of said shaft, a split collar 5 slideable on the shaft, a clamping screw threaded in said collar for locking the collar in its adjusted position to the post, an adjusting nut having right and left hand screw thread connections of low pitch with 10 said arm and collar and having an aperture through which the post extends, and liquid column indicating means supported on said arm above the base.

3. A device of the class set forth comprising a base provided with an article-supporting surface, an upright post held to the base and provided with a vertical series of teeth at one side thereof, a laterally extending arm having an aperture through which the post 15 extends, a horizontally extending shaft journaled in said arm, a pinion on said shaft meshing with the teeth on the post, a finger wheel on one end of said shaft, a split collar slideable on the shaft, a clamping screw 20 threaded in said collar for locking the collar in its adjusted position to the post, an adjusting nut having right and left hand screw thread connections of low pitch with said arm and collar and having an aperture 25 through which the post extends, an indicating-fluid receptacle supported on said arm having flexible top and bottom walls, a contact plunger reciprocably supported by the arm with its upper end engaging the lower 30 wall of said receptacle, an adjusting screw threaded in said collar for locking the collar in its adjusted position to the post, an adjusting nut having right and left hand screw thread connections of low pitch with 35 said arm and collar and having an aperture through which the post extends, an indicating-fluid receptacle supported on said arm having flexible top and bottom walls, a contact plunger reciprocably supported by the arm with its upper end engaging the lower 40 wall of said receptacle, an adjusting screw having a threaded connection with the arm and adapted to engage and flex the upper wall of the fluid receptacle, and a transparent indicator tube having a fine bore in 45 communication with the interior of the fluid receptacle.

4. A device of the class set forth comprising a base provided with an article-supporting surface, an upright post held to the base and provided with a vertical series of teeth at one side thereof, a laterally extending arm having an aperture 50 through which the post extends, a horizontally extending shaft journaled in said arm, a pinion on said shaft meshing with the teeth on the post, a finger wheel on one end of said shaft, a split collar slideable on the shaft, a clamping screw 55 threaded in said collar for locking the collar in its adjusted position to the post, an adjusting nut having right and left hand screw thread connections of low pitch with said arm and collar and having an aperture 60 through which the post extends, an indicating-fluid receptacle supported on said arm having flexible top and bottom walls, a contact 65 plunger reciprocably supported by the arm with its upper end engaging the lower wall of said receptacle, an adjusting screw having a threaded connection with the arm and adapted to engage and flex the upper wall of the fluid receptacle, and a transparent indicator tube having a fine bore in communication with the interior of the fluid receptacle.

tact plunger reciprocably supported by the arm with its upper end engaging the lower wall of said receptacle, an adjusting screw having a threaded connection with the arm and adapted to engage and flex the upper wall of the fluid receptacle, a transparent indicator tube having a fine bore in communication with the interior of the fluid receptacle, a pair of posts supported at opposite sides of the indicating tube in fixed relation therewith, a graduated plate adjustably supported on one of said posts, and a plurality of independently adjustable pointers mounted on the other of said posts. 70 75

5. A device of the class set forth comprising means for supporting an article to be tested, a support adjustable toward and from said article-supporting means, a metallic reservoir for an indicating fluid having flexible top and bottom walls and rigid sides and a rigid upwardly extending tubular boss integral with its top wall, a transparent indicator tube rigidly supported in the upwardly extending boss with its bore in communication with the interior of the reservoir, means for retachably holding the reservoir to the adjustable support, a plunger adapted to flex the bottom wall of the reservoir, a screw mounted on the adjustable support and adapted to flex the top wall of the receptacle, a post adjacent the indicator tube movable with the adjustable support, and a plurality of independently adjustable pointers mounted on said post. 80 85 90 95

6. A device of the class set forth comprising a vertically adjustable support having an aperture therethrough the lower portion of which is enlarged to form a downwardly facing recess, a cylindrical metallic reservoir seated in said recess having rigid sides and flexible top and bottom walls, the upper wall of said reservoir being formed with a tubular boss extending upwardly through the aperture in said support, an indicating tube having its lower end seated in said boss and its bore communicating with the interior of the reservoir, a closure member threaded in the lower end of said recess for removably holding the reservoir in the recess, a plunger extending through and slidably guided by said closure member, means for holding the upper end of said plunger against the bottom of the reservoir, and a screw threaded through said support with its inner end projecting within the recess and adapted to flex the top wall of the reservoir. 100
105
110
115
120

7. A device of the class set forth comprising a support, a metallic reservoir having rigid side walls and flexible top and bottom 125 walls, an indicator tube extending through said support and communicating at its lower end with said reservoir, means for removably holding said tube to the top wall of the reservoir, means coöperating with the 130

rigid side walls of the reservoir for removably clamping the reservoir against the under side of the support, adjustable means on the support for flexing the top wall of the reservoir, and article-engaging means adapted to flex the bottom wall of the reservoir.

8: A gage as defined in claim 6 and where-

in the plunger is slotted and an adjustable pin is adapted to engage the upper wall of said slot to adjust the plunger against the bottom of the reservoir.

This specification signed this 30th day of September, A. D. 1919.

CHARLES E. COATS.
